DOOR PULL

Richard C. Dyer, New Castle, Ind., assignor to New Castle Products, Inc., New Castle, Ind., a corporation of Indiana

Filed Dec. 4, 1961, Ser. No. 67,795

Term of patent 14 years

(Cl. D10—8)

FIG. 1 is a perspective view of a door pull embodying my new design as viewed from either side;

FIG. 2 is an elevational view thereof as viewed from either the front or rear;

FIG. 3 is a side elevational view thereof as seen from either side;

FIG. 4 is a plan view thereof as viewed from either the top or bottom; and

FIG. 5 is a horizontal section taken generally on the line 5—5 of FIG. 2.

The portions shown in broken lines are included for illustrative purposes only.

I claim:

The ornamental design for a door pull, substantially as shown and described.
